TOY

Heinrich Müller, Nuremberg, Germany

Application January 26, 1933, Serial No. 653,638
In Germany August 27, 1932

2 Claims. (Cl. 46—45)

This invention relates to a toy which is movable on wheels and can either be drawn or be driven by means of a wheel-work built into the mechanism. In contradistinction to known toys of a similar character the characteristic feature of the present improved toys consist in certain new and useful arrangements and combination of parts, as specified in the claims. The object of the invention is to produce certain movements, especially such resembling or imitating the movements of the legs of an animal, may be a four-legged animal, such as a dog or the like, these movements to be produced by the members constituting the mechanism, in such a manner that the respective animal etc. appears to walk or run.

A variety of constructional forms of the new toy are possible. The first set thereof is illustrated diagrammatically and by way of example in Figs. 1-5 of the accompanying drawings, on which Figure 1 is a view showing the interior of the animal's body, seen from a side thereof. Figure 2 is a similar view, the left-hand running wheel being removed and the animal's body being shown only in dotted lines. Figure 3 is a plan of the mechanism, without the animal's body. Figure 4 is a vertical transverse section in the plane A—B of Fig. 3 and seen in the direction from the right to the left, as regards Fig. 3, and Figure 5 is also a view similar to Fig. 1, but being chiefly a side-view of the toy and showing the legs, i. e. the fore legs, in a position counter to that of Fig. 1.

With this constructional form of the toy, and the driving mechanism, the body of the animal which is hollow, is open at its bottom, as shown especially in Fig. 1. Figure 6 represents a curve indicating the way of motion of the (fore) legs of the animal when being moved up and down by the mechanism while the animal is at the same time driven forward by the same.

A second set of the constructional forms is shown in Figs. 7-12, in which the mechanism is mounted upon a bottom plate upon which the hollow body of the animal is to be placed, and in which the members that constitute the hind legs of the animal are actuated by the intermediary of the running wheels, or the axle of the same, which in turn is driven by a wheel-work, as in the first set. Figure 7 is chiefly a vertical longitudinal section through the hollow body of the animal. Figure 8 is a side-view of the mechanism, including the bottom plate upon which the wheel-work is mounted. Figure 9 is a separate view of the running wheel and the connecting rod for actuating the hind legs (not shown). Figure 10 is a separate view of the cog-wheels of the wheel-

work, in side-view. Figure 11 is a plan of the complete driving mechanism. Figure 12 is a similar view, showing, however, a modification, in that separate operating members for the two hind legs are provided, instead of a common operating member as in Fig. 11.

The Figures 13-17 show constructional forms in which a driving wheel-work is dispensed with, the toy being designed for being drawn and the mechanism serving merely for moving the legs, the rotations of the running wheels being transmitted to the legs and transformed into to-and-fro movements, as will be fully described hereinafter. Figure 13 is a side-view of the toy, partly in section. Figure 14 is a plan of the mechanism. Figure 15 is a view similar to Fig. 13 and shows a further modification in which two driving mechanisms are provided, the one having a wheel-work and serving for driving the toy and actuating the hind legs, and the other serving for operating the fore legs merely by means of front running wheels, also as more fully described in the further course of this specification. Figure 16 is a plan of the mechanisms pertaining to Fig. 15, and Figure 17 shows a modification of the left-hand portion of Fig. 16, the modification lying in the cranked shaft which is in Fig. 17 so designed that the fore legs are lifted and lowered simultaneously instead of alternately. This modification can be used also in connection with the other constructional forms of the toy.

Referring to Figs. 1-5, the toy is provided with a spring wheel-work 1 built into the driving mechanism and being adapted to be wound up in known manner by means of a square key that is to be applied to the axle 2. The spring then turns a cog-wheel 3 from which the motion is transmitted to the cog-wheel 6 across the cog-wheels 4 and 5. The wheel 6 is secured to an axle 7, to the ends of which the running wheels 8 and 9 are firmly attached. To the axle 7 is affixed also a cog-wheel 11 meshing with a cog-wheel 13 affixed to an axle 12. At the ends of this axle are cranks 14 and 15, from which extend rods 16 and 17 that extend through links 18 and 19 and form at their free ends the fore legs. The rods or legs 16 and 17 rest loosely in said links and are held therein by their own weight. They are moved upwardly and downwardly, as well as forwardly and rearwardly when the cranks are rotated. The movements of the legs resemble those of a dog etc. which is splashing in water, and when the toy is running, the legs make movements similar to those of a running little dog.

Besides the fore legs, also the hind legs are moved by the mechanism. These legs are formed by the downwardly bent ends 20 and 21 of an inverted bow 20 that is turnable on a vertical pivot 23 extending downwardly from the frame of the wheel-work. The bow 20 can be moved to and fro on said pivot by means of a connecting rod 24 extending forwardly to the crank 14, to which it is jointed. The connecting rod 24 is preferably designed as an oblong rectangular frame (Fig. 2) so that it does not contact with the running axle 7 that passes through said frame which latter can now freely oscillate corresponding to the movements of the crank 14.

15 While the movements performed by the ends of the fore legs 16 and 17 are such as indicated by the curve shown in Fig. 6, the hind legs perform more a waddling movement, only forwardly and rearwardly, which, in connection with the movements of the fore legs produces an effective appearance, although the means employed are relatively simple. The distribution of the weight of the several members is such that a certain small part of the weight is carried by the hind legs, and the movements of these latter are properly timed relatively to the movements of the fore legs so that the desired appearance is obtained. It is important in this respect that the movements of the legs is in a certain definite relation to the speed of the figure when being driven forward by the wheel-work. It has been found that the effect is best when each fore leg moves thrice upwardly and downwardly while the toy has been driven forward by as much as corresponds to double the length of the toy. Owing thereto, the number of revolutions of the running axle 7 is to be somewhat larger than the number of revolutions of the running axle 12 to which the cranks 14 and 15 are jointed and from which the movements of the legs 16 and 17 are derived.

According to the size of the figure and to the type of animal it represents it is, of course, possible to depart from the details for instance as regards the diameter of the running wheels or the ratio between the cog-wheels of the wheel-work by which the axles 7 and 12 are driven.

It is, as a matter of course, also possible to provide the mechanism with a checking device or member which is released when the toy is placed upon the ground, the wheel-work commencing only now to operate. Such checking devices or members are known and do not, therefore, fall into the scope of the present invention.

55 Referring now to Figs. 7-11, there is, relatively to the first-described constructional form, the difference that the driving wheel work 1 is mounted upon a base plate 25 which forms a bottom for the hollow toy body, this latter being placed over and upon the mechanism. Instead of the guide links 18 and 19 of Figs. 2 and 3, apertures 18^a and 19^a are provided in said bottom or base plate 25, the fore leg rods extending freely through these apertures. Furthermore, the hind legs 20 and 21 are actuated by a connecting rod 24^a (Fig. 9) which is moved to and fro from the running wheel axle 7 by means of an eccentric, as shown in Fig. 9. There are in the bottom plate two parallel longitudinal slots 70 (Fig. 11) through which the feet 20 and 21 extend downwardly. The feet form also in this case the downwardly bent ends of an inverted bow, the body portion of which is located above the said bottom plate.

75 It is, however, not indispensably requisite that

the hind legs form parts of a bow as in Fig. 11. In the modification shown in Fig. 12 each hind leg is separate; it is attached to a connecting rod 24^b which is reciprocated either by means of the rear axle or by the running wheels attached thereto. Each of these connecting rods passes through a guide link 26 projecting laterally forth from the frame of the mechanism.

Although it presents certain advantages to drive the toy by means of a spring wheel-work anyhow, that is not indispensably necessary, as it is as well possible to draw the toy by means of a cord or the like, as in Figs. 13 and 14. In this constructional form, 1^a denotes the frame of the driving mechanism, in which frame an axle 7^a is supported to which the running wheels 8^a and 9^a are attached. On the same axle is a cog-wheel meshing with a counter cog-wheel affixed to the crank shaft 12 also supported in said frame. To the cranks are attached the fore legs 16 and 17 which are guided in slots 18^a and 19^a of the bottom plate 25. The hind legs 20 and 21 form also in this case parts of an inverted bow 22 which is oscillable on a pivot 23 and is oscillated by rod 24^a either from a running wheel or from the axle of the same, preferably also with the aid of an eccentric, as in Fig. 9.

The entire mechanism is, thus, actuated by the wheels being rolled along the ground, that is to say, by drawing the toy directly by means of a cord or the like, whereby the axle 7^a will be turned and the fore legs will be operated by the intermediary of the set of wheels, whereas the hind legs will be actuated from the running wheels or their axle either as in Figs. 1-5 or in Figs. 6-11 100 or in Fig. 12. In every case the mechanism is turned by the friction arising between the running wheels and the ground when the toy is being drawn.

It is, finally, also possible to design the device 115 in this way that the fore legs are operated by separate running wheels rotated by friction, as in the preceding case, whereas moving the toy forward is effected by a wheel-work provided for this purpose, as well as for operating the hind wheels. 120 A thus designed constructional form is shown in Figs. 15 and 16. On the bottom plate are mounted a frame 1^b for the front-wheel axle and spring wheel-work 1^b for the driving wheels which are secured to the rear axle. This wheel-work is to 125 be wound up by means of the axle 2. The driving wheels 8^b and 9^b are secured to the driving shaft 7; said wheels extend downwardly through slots of said bottom plate. Also the front running wheels extend downwardly through slots of the 130 bottom plate. The rotary motion is transmitted from the wheel-work to the axle 7 by a set of cog-wheels, and is transmitted from the running wheels to the fore legs also by cog-wheels, as will now be clear without further details. The 135 arrangement of the fore legs is the same as in Fig. 14, and the arrangement of the hind legs is also the same as in said figure.

Instead of arranging the cranks for the fore legs at 180° relatively to one another, as in Figs. 11, 12, 14 and 16, in which case said legs are lifted and lowered alternately, it is also possible to have the two cranks, or crooked portions of the driving shaft respectively, extend in the same direction, as in Fig. 17, the two fore legs being then lifted 145 at the same time and lowered at the same time, as will also be clear without any further explanation.

I wish it to be understood that I do not limit myself merely to the details shown and described 150

solely by way of example. Various departures thereof are possible without departing from the inventive idea. Thus, for instance, as regards the constructional form shown in Figs. 15 and 16, the 5 fore legs may be actuated by the means employed in said constructional form for the hind legs, and these latter legs may be operated by the means used in the said constructional form for the fore legs.

10 I claim:

1. In a toy comprising a hollow body representing the body of a quadruped, legs extending forth from said body, cranks to which said feet are hinged, and means for rotating said cranks, in 15 combination with the said feet, a stationary member having slots through which the feet extend and which give them a reciprocating motion in a vertical direction while they are reciprocated in a

horizontal direction by the said cranks so as to produce the appearance of the quadruped running on its feet when the toy is in operation.

2. In a toy comprising a hollow body representing the body of a quadruped, wheels supporting said body, means for turning said wheels, legs extending forth from said body, cranks to which said feet are hinged, and motion-transmitting means between the means for rotating said wheels and said cranks, a stationary member having slots through which the feet extend and which give them a reciprocating motion in a vertical direction while they are reciprocated in a horizontal direction by the said cranks so as to produce the appearance of the quadruped running on its feet when the toy is in operation.

HEINRICH MÜLLER.
